SUPERVISORY CONTROL PANEL

Filed Dec. 6, 1930

UNITED STATES PATENT OFFICE

OTTO PLECHL, OF PFAFFSTATTEN, NEAR VIENNA, AND JOHANN LATZKO, OF VIENNA,
AUSTRIA, ASSIGNEES TO AKTIENGESELLSCHAFT BROWN, BOVERI & CIE, OF BADEN,
SWITZERLAND, A JOINT-STOCK COMPANY OF SWITZERLAND

SUPERVISORY CONTROL PANEL

Application filed December 6, 1930, Serial No. 500,592, and in Germany December 7, 1929.

This invention relates to improvements in supervisory control panels and particularly to such panels as are illuminated to indicate that the medium to be controlled is present.

Supervisory control panels of the character above mentioned are usually formed with either arbitrary or conventional symbols arranged diagrammatically thereon to illustrate the several portions of a distributing system in which the flow of gases, liquids or electricity is to be controlled. Such panels are also required to show the conditions existing in the medium to be controlled and must, therefore, be provided with indicating measuring instrument. In a control panel, it is desirable that the portions of the installation in which the medium to be controlled is flowing or is under pressure be illuminated while the portions of the installation not containing the medium be unilluminated or be illuminated in a different color. It is, therefore, necessary that the control panel be so constructed that all possibility of mistake as to the indications thereof are avoided.

It is, therefore, among the objects of the present invention to provide a supervisory control panel for flowing media distributing installations in which transparencies symbolize the distributing installation.

Another object of the invention is to provide a supervisory control panel for flowing media distributing installations in which the illumination of the symbolic transparencies indicates the presence or flow of the media.

Another object of the invention is to provide a supervisory control panel of the character above mentioned in which the symbolic transparencies are edged with colored bands to designate the media flowing therethrough.

Objects and advantages, other than those above set forth, will be apparent from the following description when read in connection with the accompanying drawing in which:

Figure 1 shows a front face portion of a supervisory control panel constructed according to the present invention; and

Figure 2 is a schematic diagram illustrating apparatus and circuits whereby con-

ditions existing in an electric circuit may be indicated on the control panel arranged according to Figure 1.

Referring more particularly to the drawing by characters of reference, the reference 55 numeral 1 designates a fragment of a panel which is preferably of glass plate coated with a dark substantially opaque coating. A quantity of the panel coating is removed as shown at 2 to form an entirely transparent path indicating a conduit or a conductor which is edged with bands 3 of an entirely opaque coating different from the coating on other portions of the panel for the purpose of defining the conduit or conductor 2 more clearly when the same is illuminated from the rear by any of the numerous well-known methods. The edgings then indicate the walls or the outer surfaces of a sectioned conduit or conductor. The dark coating of the panel 1 is likewise removed as shown at 4 in such manner as to indicate, diagrammatically by use of a symbol, some means such as a switch or valve for blocking the conduit or conductor 2 against the flow of the medium to be controlled. The transparent valve symbol 4 is edged with an opaque coating 5 on the panel 1, as is the case for the conductors, to define the transparent areas of the valve 4 most clearly. 80

In any installation for the distribution of a flowing medium it is necessary that indicating measuring instruments be provided to show such conditions of the medium as the quantity, pressure, velocity, etc. Such measuring instruments should, of course, be of the nature and types adapted for the measurement and indications of conditions of the particular medium to be controlled. In Figure 2 of the drawing I have, therefore, 85 illustrated an electrical instrument 17 having its operating coil 17 connected with the conductor 18, across a shunt 19, of an electric circuit including an electric generator 20 supplying a consuming device 21. The 90 measuring device carries an oscillating member 22 secured to the core of the instrument coil as shown.

The member 22 may be formed as a pointer or as a plate having a slot, or other 95

configuration. A lamp 23 is placed behind the electrical instrument 17 and the light therefrom focused upon the member 22 of the instrument by a lens 24. Light is projected from the lamp 23 across the path of movement of the member 22 onto the scale 10 by an adjusting lens 25. Thus any movement of the member 22 by the measuring instrument 17 will, if the member be formed as a pointer, cause the lengthening or shortening of the shadow 9 upon the scale 10 thereby producing in the diagram a clearly visible indication of current, or other conditions, of the circuit of the generator 20 and conductor 18. If, on the other hand, the member 22 be formed as an opaque sheet with a cutout slot or opening of other configuration, any movement of the member 22, by the measuring instrument, will cause the lengthening or shortening of a "light arrow" projected upon the scale 10 instead of the shadow 9. The scale 10 is surrounded by an opaque edging 11 which emphasizes the distinction between the shadow 9 and the scale 10. When the diagram is to be employed for indicating the conditions of certain medium, particularly the pressure, quantity, temperature, purity, homogeneity, or other conditions of the medium, the instruments may be arranged directly in or on the conduit section 2. When not placed on the conduit section 2, it is desirable that the point at which the measurement is taken be indicated by connecting the instrument with a scale 7 or 8 with the point of measurement by a lead line of a different color shown at 13 so formed as to distinguish from the other portions of the panel. It will be understood that a plurality of instruments may be so arranged as to obtain shadows of the respective indicators on the same scale which then permits a ready comparison of the various values shown.

In any case, even through the shadows 9 indicate the direction of flow, it is desirable, at suitable points along the conduit section 2, to provide arrows pointing in opposite directions as at 15 and 16 to show, by illumination or the absence of illumination, the direction of flow of the controlled medium.

When the panel is used to indicate the flow of different media or media under different conditions as a steam distributing installation handling superheated steam, saturated steam, condensate or cooling water, either the edgings 3 and 11 are of different colors or different colored lamps are arranged behind the transparent symbolic panel portions 2 and 10. Illumination of the transparent portions then indicates the presence and the different colors indicate the conditions or the type of the media to be controlled. The degree or color of the illumination may also indicate the conditions of the medium in the several conduits.

It will be understood of course that the illuminated supervisory control panel illustrated and described may be operated by remote control due to operation of the various devices symbolized on the panel or that a switch desk having auxiliary controlling apparatus preferably arranged in a diagrammatic manner similar to that shown on the panel may be arranged adjacent the panel to supervise the control of the devices indicated on the panel. Each piece of auxiliary apparatus is preferably mounted directly adjacent or at the point of the operating device which is symbolized on the panel. It is then possible to determine exactly and to control the distributing installation properly dependent on the condition of the apparatus on the desk as shown by the control panel.

Although but one embodiment of the present invention has been illustrated and described, it will be apparent to those skilled in the art that various changes and modifications may be made therein without departing from the spirit of the invention or from the scope of the appended claims.

The invention claimed is:

1. In a control panel for supervising the distribution of flowing media, a transparent wall, a substantially opaque coating for said wall, portions of said coating being removed to form symbolic transparencies and bands of an opaque color defining the edges of the symbols.
2. In a control panel for supervising the distribution of flowing media, a transparent wall, a substantially opaque coating for said wall, portions of said coating being removed to form symbolic transparencies, and bands of an opaque coating defining the edges of the symbols, the colors of said coating and of said edging bands differing.
3. In a control panel for supervising the distribution of flowing media, a transparent wall, a substantially opaque coating for said wall, portions of said coating being removed to form symbolic transparencies, bands of an opaque coating defining the edges of the symbols and transparent scales arranged on said wall to receive indications of the conditions of the media.
4. In a control panel for supervising the distribution of flowing media, a transparent wall, a substantially opaque coating for said wall, portions of said coating being removed to form symbolic transparencies, bands of an opaque coating defining the edges of the symbols, transparent scales arranged in the symbolic transparencies, and transparent scales arranged adjacent the symbolic transparencies, said scales receiving indications of the conditions of the media.
5. In a control panel for supervising the distribution of flowing media, a transparent wall, a substantially opaque coating for said

wall, portions of said coating being removed to form symbolic transparencies, bands of an opaque coating defining the edges of the symbols, transparent scales arranged in the symbolic transparencies, and transparent scales arranged adjacent the symbolic transparencies, said scales receiving indications of the conditions of the media, a lead line connecting said adjacent scales with the point of the symbolic transparencies at which an indication of the conditions in the media is desired.

6. In a control panel for supervising the distribution of flowing media, a transparent wall, a substantially opaque coating for said wall, portions of said coating being removed to form symbolic transparencies, and bands of an opaque color defining the edges of the symbols, the colors of said edging bands differing from the color of said coating, and the colors of said edging bands differing dependent on the media indicated in the symbolic transparencies.

7. In a supervisory control panel for supervising the distribution of flowing media, a transparent wall, a substantially opaque coating for said wall, portions of said coating being removed to form symbolic transparencies, bands of an opaque coating defining the edges of the symbols, and transparencies arranged to indicate the direction of the flow of the media.

In testimony whereof we have hereunto subscribed our names this 19th day of November A. D. 1930.

JOHANN LATZKO.
OTTA PLECHL.
